CLAIM

The ornamental design for a seat panel for office chair, as shown and described.

DESCRIPTION

FIG. 1 is a front elevation view of a seat panel for office chair showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a right perspective view thereof; and,

FIG. 8 is a bottom perspective view thereof.

The dashed broken lines in the drawings are for the purpose of illustrating unclaimed portions of the seat panel for office chair and form no part of the claimed design.
